The ornamental design for an upper rib pattern for a planer, as shown and described.

DESCRIPTION

FIG. 1 is a left side perspective view from the front of a upper rib pattern for a planer showing my new design;
FIG. 2 is a left elevational view of my design;
FIG. 3 is a right elevational view of my design;
FIG. 4 is a front elevational view of my design; and,
FIG. 5 is a back elevational view of my new design.
In the attached drawings, any broken line illustration is not part of the design sought to be patented.
